TOY BATTLESHIP

Edward W. Koepnick, Dayton, Ohio

Application October 18, 1947, Serial No. 780,649

2 Claims. (Cl. 273—102.1)

1

This invention relates to a toy battleship and more particularly to a battleship that has the appearance of being demolished when hit by a missile from a toy submarine of the type disclosed in my copending application, Serial No. 627,252, filed November 7, 1945 and now abandoned.

This application is a continuation in part of the above identified application and is directed to an improved form of toy battleship.

An object of this invention is to provide an improved toy battleship construction which is both inexpensive to manufacture and durable.

Another object of this invention is to provide a plastic construction which may be formed by the use of simple molds using a minimum amount of material.

Other objects and advantages reside in the construction of parts, the combination thereof and the mode of operation, as will become more apparent from the following description.

In the drawings;

Figure 1 is a plan view of a toy simulating a battleship;

Figure 2 is an elevational view of the toy battleship shown in Figure 1;

Figure 3 is a plan view of a battleship shown in Figures 1 and 2 with the deck and super-structure removed so as to show the construction and arrangement of the spring mechanism used for throwing the deck and super-structure up in the air;

Figure 4 is a vertical sectional view taken substantially on line 4—4 of Figure 3;

Figure 5 is a vertical sectional view on an enlarged scale and taken substantially on line 5—5 of Figure 3; and

Figure 6 is a fragmentary sectional view taken substantially on line 6—6 of Figure 3.

As shown in the drawings, the battleship comprises a molded plastic main body or hull 200 which is adapted to rest on the floor or other support and which serves as a support for a flat piece of plastic or other material 202 resembling the deck of a boat. Suitable super-structure elements such as the smoke stack unit 204 and the gun turrets 208 loosely rest on top of the deck member 202 so that when the deck member 202 is thrown up into the air by a snap mechanism to be described hereinafter, the gun mounts and the super-structure are thrown clear of the deck so as to make the demolition of the battleship seem very realistic.

The snap mechanism used for demolishing the battleship resembles the spring mechanism of a mouse trap and comprises a spring or snap mem-

ber 210 which is pivotally supported on a pin 212 carried by a pair of spaced sheet metal supports 214. A coil spring 216 is provided by biasing the snap member 210 from the full line position in which it is shown in Figures 3 and 4 to the dotted line position in which it is shown in Figure 4. A slideable trigger or latch 218 is arranged to hold the snap member 210 down beneath the upper edge of the ship's hull when the snap mechanism is in the cocked position. When the outer end of the latch 218 is hit by means of a toy torpedo, the latch element will move inwardly so that the notch portion 220 provided in the one edge of the latch 218 clears the hump shown in the snap member 210.

In order to improve the action of the latch element 218, I have provided a guide pin 222 which is embedded in the plastic part of the ship and which projects through the diagonal slot 224 provided in the latch. By virtue of the above described pin and slot arrangement it is obvious that the latch element 218 moves at an angle away from the spring or snap member 210.

The latch element 218 is slidably held in place between a ledge 230 (provided as an integral part of the molded hull) and a plastic insert 232 which is held in place by means of a plurality of screws 234. The hull of the ship is reinforced by means of suitable ribs 236 provided at appropriate locations as indicated.

The supports 214 are flat stampings which pass through openings 240 provided in the specially constructed reinforcing rib 242. The upper ends of the supports 214 are apertured as shown for receiving the pin 212 and the lower ends are bent at right angles to the main body thereof so as to hold the supports in place. This construction is very inexpensive and eliminates the need for the use of screws and bolts which might jar loose and yet makes it possible to quickly replace a broken support if necessary.

While it is preferable to use molded plastic material for the main ship structure, some of the features of this invention are equally applicable to ships made from metal, wood, cardboard or any other type of material.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

2

It will be noted that in the event the spring 210 breaks, a new spring may be inserted by hand without the need for any tools by merely sliding the pin 212 sideways a distance just enough to disengage the one end of the pin from the aperture in the post 24. This makes it possible to replace the broken spring after which the pin is easily returned to the position shown.

The spring tension may be reduced by unhooking the one end of the spring from the snap member 210. This is usually done when the toy is to be used by smaller children.

While Figures 1 and 2 show the deck member 202 resting on top of the hull 200, it is preferable to use a deck such as the deck 202a shown in Figure 4 which fits down into the hull. This prevents the deck from sliding sideways on the hull when the torpedo misses the target 218 but hits the hull. The deck 202a rests on the ledges 236a formed by the end reinforcing ribs as shown. The superstructure elements have not been shown in Figure 4, but these would be similar to those shown in Figures 1 and 2.

Having thus described my invention, I claim:

1. A toy battleship having a first molded plastic shell member resembling a bottomless and a deckless hull of a battleship, said shell member including transversely extending reinforcing ribs, a substantially flat plate resting on said shell member so as to simulate the deck of the battleship, superstructure elements freely resting on said plate, means for throwing said plate and said superstructure elements clear of the hull, said last named means including a snap mechanism, said snap mechanism comprising a snap spring mounted on one of said reinforcing ribs and having a loop portion adapted to flip through 180° when the spring is actuated from a loaded position to an unloaded position, a latch for holding the spring in loaded position, said latch comprising a one piece sheet metal stamping forming a reciprocating plunger having a target portion projecting from one side of said shell member, said shell member including a transversely extending ledge for reinforcing said shell member adjacent said latch and for slidably guiding said plunger, one of said reinforcing ribs being substantially U-shaped in cross section and being arranged in the path of said loop portion so as to

serve as a stop therefor at the end of the snap operation.

2. A toy battleship having a first molded plastic shell member resembling a bottomless and a deckless hull of a battleship, said shell member including transversely extending reinforcing ribs, a substantially flat plate resting on said shell member so as to simulate the deck of the battleship, superstructure elements freely resting on said plate, means for throwing said plate and said superstructure elements clear of the hull, said last named means including a snap mechanism, said snap mechanism comprising a pivot pin and a snap spring mounted on said pivot pin and having a loop portion adapted to flip through 180° when the spring is actuated from a loaded position to an unloaded position, a pair of sheet metal mounting posts projecting through one of said ribs for supporting said pivot pin thereon, each of said mounting posts comprising a sheet metal stamping having a bearing aperture for said pivot pin at its upper end and a right angle projection at its lower end for preventing removal thereof, and a latch means for holding the spring in loaded position, said latch means comprising a reciprocating plunger having a portion projecting from one side of said shell member, said shell member including a transversely extending ledge for reinforcing said shell member adjacent said latch means and for slidably guiding said plunger, one of said reinforcing ribs being substantially U-shaped in cross section and being arranged in the path of said loop portion at one end of its path of travel so as to serve as a stop therefor, another of said reinforcing ribs serving as a means for supporting said snap spring.

EDWARD W. KOEPNICK.
